APPARATUS FOR MIXING LIQUIDS

Filed June 27, 1932

UNITED STATES PATENT OFFICE

EDWARD DORSEY, OF PHOENIX, ARIZONA

APPARATUS FOR MIXING LIQUIDS

Application filed June 27, 1932. Serial No. 619,594.

This invention relates to a process of mixing liquids mechanically and uniformly in certain ratios or percentages which are fixed after adjustment but which may be adjusted 5 to vary said ratios or percentages as desired.

The invention is capable of use in many relations but is particularly valuable in the sterilization field where it is frequently desired to introduce disinfecting or germicidal 10 solutions into water at the rate of a very small percentage of the germicide to a very large percentage of water.

While the principles of the invention may be employed in conjunction with municipal 15 water plants, swimming pools, and the like, I contemplate, as one very important use of the invention, its incorporation into a highly ornamental, attractive and interesting sterilizer for use on soda fountains to sterilize and disinfect the water used to wash the 20 drinking glasses, spoons, dishes, and the like, there employed.

In the particular embodiment of the invention which I have shown for purpose of 25 illustration, the sterilizer comprises a glass structure, into one compartment of which city water is discharged and from which compartment the city water is conducted to the sink or rack or other point of use; the 30 flow of the water being used to automatically draw from a second compartment a colored disinfecting fluid or germicide in minute quantities, such for example, as one part of the germicide to one-billionth part of wa- 35 ter.

The device is made, in the main, of glass, so that the change of color of the water will be carried out in view of the patrons who will thereby be apprized that the establishment 40 in question is disinfecting the water used for washing the implements employed, and this has been found to be highly efficient in attracting trade.

In the accompanying drawing

Figure 1 is a view partly in elevation and partly in section of a device constructed in accordance with the invention.

Figure 2 is an enlarged sectional view 50 through the adjustable mixing valve hereinafter described.

In the drawing, 5 indicates a regulating valve disposed in a city water supply line 6, and 7 indicates a conventional type of water pressure gauge. The supply line terminates in a goose neck 8, a thread 9 of 55 which receives a packing nut 10 which bears upon a rubber or like gasket 11 and binds between said nut and an enlarged element 12 of a mixing tube 13, the web 14 of a hood 15. A reflector 16 is mounted upon the top 60 of the hood 15 and carries an electric light 18 which aids in illuminating the interior of the compartment 19. This compartment receives the disinfecting and germ destroy- 65 ing liquid.

The bore of the mixing tube constitutes a part of the conduit by which the water is delivered into the mixing tube 20. The chambers 19 and 20 are separated from each other by a partition 21. An outlet pipe 22 has a 70 baffle cone 23 disposed over its upper end and this pipe passes through the bottom of the glass receptacle 24 within which the chamber 20 is located and through a base 26. Packing nuts 26 and 27 bind these parts together 75 and compress packing washers 28, 29 and 30 in such a way as to bring about a fluid tight joint.

A U-tube 31 establishes communication between the interior of the compartment or chamber 19 and a port 32 which leads to the bore 33 of the mixing chamber. The passage of the disinfecting fluid through the U-tube and port 32 is controlled by a valve 34. The stem of this valve is slotted, as indicated at 35, for the reception of a screw driver or like tool and said valve passes through a packing gland 36. The flow of the germicidal liquid through the port 32 may be very minutely adjusted by proper adjustment of valve 35, and by making bore 33 of the mixing tube of the shape shown, namely, downwardly flaring; the flow of the city water through said bore will draw a minute amount of the liquid through the tube 31 and the port 32. The light 18 makes it possible for the patrons to see what is going on and to observe the gradual change of color which takes place between the time that the water enters compartment 20 and the time that it 95 100

finds its way out of said compartment around and beneath the baffle cone 23.

The water flows continuously into the soda fountain sink and in and about the water rack 5 so that the dish water is continuously and automatically disinfected in order to kill trench mouth germs and all sorts of communicable diseases. The principle here shown and described is applicable to restaurants, hotels, dairies, bottling plants, 10 municipal water plants, etc., so that any kind of drinking or wash water may be kept free from any kind of living cultures or organisms or from any source of contamination which 15 would pollute the water by odor or otherwise.

It will be observed that the partition 21 constitutes the integral bottom of the upper portion of the glass receptacle, the interior 20 of which constitutes chamber 19, and this bottom fits down into that part of the receptacle, the interior of which constitutes chamber 20 and may be held therein by fusing, cementing, or otherwise.

25 It is to be understood that the invention is not limited to the precise construction set forth, but that it includes within its purview whatever changes fairly come within either the terms or the spirit of the appended claims.

Having described my invention, what I claim is:

1. A device of the character described comprising a glass receptacle divided into two 35 compartments, one of which contains a disinfecting fluid, a water flow line passing through said compartment and discharging into the other of said compartments, said water flow line comprising a mixing tube, 40 and a suction line connected to the said mixing tube and receiving its supply from the chamber containing germicidal liquid, the arrangement being such that the flow of the water through the water flow line draws the 45 germicidal solution into the water flow line.

2. A device of the character described comprising a glass receptacle divided into two compartments, one of which contains a disinfecting fluid, a water flow line passing 50 through said compartment and discharging into the other of said compartments, said water flow line comprising a mixing tube, a suction line connected to the said mixing tube and receiving its supply from the chamber 55 containing germicidal liquid, the arrangement being such that the flow of the water through the water flow line draws the germicidal solution into the water flow line, a discharge pipe leading from the last named 60 compartment, and a baffle between said pipe and the water flow line.

In testimony whereof, I hereby affix my signature.

EDWARD DORSEY.
